UNITED STATES PATENT OFFICE.

ANDREW C. HAUCK, OF BROOKLYN, NEW YORK, ASSIGNOR TO WILLIAMSBURG WOOD HEEL COMPANY, OF BROOKLYN, NEW YORK, A CORPORATION OF NEW YORK.

MACHINE FOR DRIVING METAL DOWELS.

Application filed July 30, 1923. Serial No. 654,524.

This invention relates particularly to the reinforcement of wooden heels by the driving of a metal pin or so-called dowel therein, and the general objects of the invention 5 are to provide a simple and practical machine for this and similar purposes.

More specific objects of the invention and the novel features of construction, combination and arrangement of parts which enable the attainment of the same will appear 10 more fully as the specification proceeds.

In the accompanying drawings forming part of this specification the invention is illustrated embodied in a practical commercial 15 form, but it is to be understood that the structure may be varied without departure from the true spirit and scope of the invention as hereinafter defined and claimed.

Figure 1 in the drawings is a top plan and 20 part sectional view of the machine, the sectional portion of this view being taken on substantially the plane of line 1—1 of Figure 2.

Figure 2 is a side elevation of the machine 25 with the feed hopper appearing in section.

Figure 3 is a vertical sectional view on substantially the plane of line 3—3 of Figure 2.

Figures 4 and 5 are similar views on substantially the planes of lines 4—4 and 5—5 of Figure 2.

Figure 6 is a detached perspective view of the operating slide.

In the present disclosure the dowels 7, of 35 proper length, are automatically fed from a hopper 8 down through a feed chute 9 into position, one at a time, in front of a plunger 10 which drives the dowel into a seat provided for it in the heel 11 positioned on 40 the work, rest or holder 12.

The hopper is made up of an outer partly cylindrical stationary casing having a discharge slot 13 in the bottom thereof opening 45 into the top of the vertical feed chute 9, with an open drum 14 rotatably supported within such casing and provided in its annular wall with a plurality of slots 15 of slightly larger size than the dowels being handled. This slotted drum operates to individualize and 50 line up the dowels with the feed chute and is shown as fixed by screws 16^a to a hub 16 journaled in the back wall of the casing and as having its front wall 70 pivotally sup-

ported on the shaft 71, fixed in the front wall of the hopper casing.

The top of the hopper and drum are shown in Figure 2 as open for the purpose of charging the hopper. In this same view and in Figure 3 a segmental guard 17 is shown as supported by the lower part of a segmental wall 17^a, in position overstanding the rim or annular wall of the slotted drum so as to break the fall of the dowels thrown into the hopper, and provide, with the lower wall of the casing, a segmental channel 18 60 extending over the top of the feed chute and of a size to pass only a single dowel. From Figure 3 it will be seen that the dowels will roll off the ends of this guard into the slots in the drum and be carried thereby through 65 the passage beneath the guard and into the top of the feed chute.

At the bottom of the feed chute the dowels come to rest in a seat 19 which as shown in Figure 2 is in line with the driving plunger 75 10 and is open at both ends to permit the entry of the plunger at one end and the exit of the dowel at the opposite end.

The drive plunger is shown as carried by a slide 20 reciprocating in guides 21 and actuated by a lever 22 pivotally supported at 23. This lever may be provided with a pedal at its lower end so as to be operated by foot power and is shown as acted on by a spring 24 to return it to the position indicated in Figure 2 after each actuating impulse. A pivotal sliding connection between the upper end of the power lever and slide is provided in the illustration by a pin 25 extending from opposite sides of the slide into engagement with rectangular bearing blocks 26 slidably fitting in guide forks 27 at the upper end of the lever and spaced to stand at the opposite sides of the slide. These sliding pivot blocks are shown as confined in 90 their forks by the overstanding cover plates 28.

The reciprocating motion of the slide is utilized in the present disclosure to impart rotary movement to the sorting drum of the 100 hopper, the slide being provided for the purpose with an upstanding post 29 carrying a roll 30 operating in an inclined slot 31 in a plate 32 sliding in vertical guides 33 and having an offset arm 34 carrying a rack 35 105 which meshes with a pinion 36 on the hub.

16. From this it will be seen that as the actuating lever rocks back and forth the cam plate 32 will be raised and lowered and the pinion will be turned to swing the feed drum and thus bring the dowels one at a time into the top of the feed chute, Figure 3 indicating this action as having been just effected.

10 The dowel which is about to be driven is preferably segregated from those above it, by means consisting in the present illustration of a cross slide 39 operating in a guide 40 intersecting the lower end of the feed chute at a point just above the driving seat 19. The 15 inner end of this cross slide is shown in Figure 3 as pointed or beveled at 41 so as to enter readily between the lowest and next dowel and lift the upper column of dowels entirely clear of the bottom one.

20 The cross slide is actuated in the present disclosure from the main driving slide through the medium of a rock lever 42 pivoted at 43 and engaging at one end with a pin 44 on the cross slide and having its opposite end positioned to be actuated by a dog 45 carried by the main slide. This dog is shown as pivoted at 46 on a stud 47 projecting from one side of the upstanding post 29 on the slide and as yieldingly held against a stop shoulder 48 on the stud by the spring 49. This pawl thus can yield on the forward stroke of the main slide and so during such movement it rides up over a shoulder 50 on the inner edge of the rock lever and over the 35 top of such lever until at a point substantially at the end of the forward stroke of the slide it drops down in front of the cam shaped forward edge 51 of the lever, substantially as indicated by the dotted lines in 40 Figure 1.

Upon the return stroke of the main slide the dog bears against the stop 48 and so operates as a rigid abutment which by its travel over the inclined edge 51 rocks the 45 lever 42 so as to draw out the cross slide and permit the column of dowels in the feed chute to drop. As the main slide approaches the rearward or outward end of its stroke the dog passes free of the end of the rock 50 lever, as will be clear from Figure 1, thereby permitting the spring 52 to assert itself and draw the cross slide inwardly so as to separate and lift the column of dowels off the lower dowel, as in Figure 3, leaving the 55 lower dowel positioned in its seat ready to be driven upon the next stroke of the driving plunger.

It will be clear from the description thus far that while both the dowel feeding and 60 the dowel segregating devices are actuated from the dowel driving mechanism, the actuation of the slide takes place upon the idle or return stroke of the driving mechanism so that upon the active stroke of such mechanism the main force is applied to the purpose

of driving the dowel into the heel or other article.

The work holder 12, which, in the present disclosure is designed for the support of a wooden heel, is shown in the form of a block 70 pivotally adjustable about a stud 53 on which it is removably held by a cap screw 54 and secured in its different angularly adjusted positions by a set screw 55.

In the illustration the stud or post 53 is 75 vertically guided in a socket 56, being shifted therein by an adjusting screw 57 shown in Figure 5 as rotatably held in the bottom of the socket and having a screw-threaded engagement in the bottom of the post. In 80 this view the socket is indicated as of split construction, having its two parts secured together by a bolt 58 which serves to lock the post in the position to which it has been adjusted by screw 57.

A back and forward adjustment of the work holder with respect to the dowel driver is also provided in the illustration by mounting the work holding post in a block or carriage 59 slidable in a guideway 60 and having 90 a lug 61 engaged by a screw 62 which is rotatably held in an open bearing 63 on the base of the machine. One side of the guideway 60 is shown as provided by a clamp block 64 (Figure 5) having an inclined face 95 overstanding the correspondingly inclined face of the base 59, which clamp is adjustably secured by a screw bolt 65. Upon loosening this screw bolt it will be seen that the base can be shifted toward or away from the dowel driver by means of adjusting screw 62, to suit different lengths of dowels, for instance, and that as soon as the proper adjustment is secured, the base may be fastened in that relation by means of the clamp 105 described.

To enable proper positioning of the heel or other article upon the work support, an edge gage is shown provided on the work holder comprising a gage piece 66 slidably guided in a slot 67 in the block 12 and shifted by means of a screw 68 having a rotatable bearing in a lug 69 at the end of the block and having a screw-threaded engagement in the body of the adjustable gage piece. By 110 means of this screw the gage is positioned so that the operator needs simply to thrust the edge of the heel against the gage to bring the socket in the heel into register with the dowel driving passage.

To adapt the machine to the handling of dowels of different length the hopper may be equipped with a gage plate shown at 72 in Figure 2 as adjustably secured upon the shaft 71 in opposition to the segmental wall 125 17^a. By the relative adjustment of these two walls it will be seen that dowels of longer or shorter length can be accurately positioned within the hopper.

Similarly, the feed chute 9 may be ad- 130

justed for different lengths of dowels by providing it with an end wall or plate 73 slidably guided on pins 74 and clamped in adjusted relation between the side walls of

5 the chute (Figure 1) by a screw 75 which clamps the sides of the chute together upon this intervening gage plate. This gage plate, it will be understood, is adjusted in accordance with the adjustment of the end gage 72

10 of the hopper.

The hopper and feed chute in the construction shown are both detachably mounted upon the supporting frame, the hopper being carried by the brackets or standards 76 secured 15 on the base by screws 77, and the chute being attached to the bottom of the hopper and fitting at its lower end into a slot 78 provided for the purpose in the base or supporting frame. It will be seen from 20 this that after removal of the screws 77 the hopper and feed chute may be lifted entirely free of the machine for the purpose of emptying out the dowels and adjusting it for other length dowels, for instance. This 25 removability is particularly advantageous in facilitating accurate adjustment of the hopper and feed chute, one with respect to the other.

What I claim is:—

30 1. In a machine of the character disclosed, a reciprocating slide, a drive plunger carried thereby, a seat open at the top and in longitudinal alinement with said plunger, a delivery chute over the open top of said

35 seat, a supply hopper having a delivery drum with slots for registering with the head of the chute and connections from the slide for imparting rotary movement to the delivery drum.

40 2. In a machine of the character disclosed, a reciprocating slide, a drive plunger carried thereby, a seat open at the top and in longitudinal alinement with said plunger, a delivery chute over the open top of said

45 seat, a supply hopper having a delivery drum with slots for registering with the head of the chute, connections from the slide for imparting rotary movement to the delivery drum, a cut-off slide intersecting the lower end of the delivery chute and connections from the main slide for operating said cut-off slide.

50 3. A combination as in claim 1 with a cut-off slide intersecting the lower end of the delivery chute and operating connections from the main slide for said cut-off slide, the operating connections for both the delivery drum and cut-off slide being effective for operating said devices upon the retractive or return stroke of the main slide.

55 4. In a machine of the character disclosed, a supply hopper having a stationary casing with a discharge outlet in the bottom of the same, a segmental guard overstanding said outlet and a delivery drum having an

annular rim traversing the space between the segmental guard and adjacent wall of the casing and provided with article receiving pockets therein.

5. A combination as in claim 4 with means for intermittently imparting rotary movements of the drum to bring the article pockets into register with the discharge outlet.

6. The structure of claim 4 with a reciprocating plunger, a delivery chute extending from the outlet passage to a seat in line with the plunger and connections from the reciprocating plunger for imparting intermittent rotary movements to the delivery drum.

7. A combination as in claim 4 with a delivery chute in line with the outlet passage, a cut-off slide at the foot of said delivery chute and a rock lever actuated by the main slide and having a connection with the cross slide.

8. A combination as in claim 4 with a delivery chute in line with the outlet passage, a cut-off slide at the foot of said delivery chute and a rock lever engaged with the cross slide and having a one-way actuating connection with the main slide.

9. In a machine of the character disclosed, a main slide, a cross slide and connections between the two, including a rock lever engaged with the cross slide and having a cam face for engagement by a yielding pawl carried by the main slide.

10. In a machine of the character disclosed, a horizontally adjustable base, a vertically adjustable post carried thereby and a work holder angularly adjustable and removably engaged on said stud.

11. The structure of claim 10 with a gage piece adjustable on said work holder.

12. In combination, a hopper comprising an outer stationary casing having a discharge slot in the bottom thereof and a guard overstanding said discharge slot, a drum rotatably supported within the casing and having a slot for registry with the discharge slot and means for oscillating said drum to carry the slot therein between the discharge slot and the overstanding guard.

13. In combination, a hopper having a discharge slot in the bottom thereof, a sorting drum rotatably supported within the hopper and having a slotted rim positioned to traverse the discharge slot, a supporting shelf within the hopper over the slotted rim of the drum and relatively adjustable end plates for gaging the ends of articles resting on said shelf.

14. The structure of claim 13 with a chute in line with the discharge slot and having an adjustable gage wall.

15. In combination, a hopper having side walls and a discharge outlet, a stationary shaft supported at one side wall and a hub

journalized in the other side wall, article positioning means supported by the stationary shaft, article feeding means supported by the hub and means for imparting feeding movements to said hub.

16. In combination, a hopper having a discharge outlet, a sorting element mounted for rotary movements within the hopper and having an article pocket for registry with the discharge outlet, relatively adjustable stationary gage walls within the hopper and an article supporting shelf between said relatively adjustable walls and over the discharge outlet.

17. In a machine of the character disclosed, a dowel guiding passage, a driver for a dowel in said passage, a feed chute for supporting a stack of the dowels in superposed order over the guide passage, a transversely operating cut-off slide for supporting and separating the dowels in the stack above the dowel in the guide passage, a heel supporting block adjustable through a variety of angles to bring the dowel passages in the heels in line with the guide passage, a hop-

per above the feed chute and means in said hopper for sorting and feeding the dowels into the top of the feed chute.

18. In a machine of the character disclosed, a supply hopper having a discharge outlet, a guard over that portion of the hopper containing said outlet and spaced therefrom in substantial parallelism, a separator traveling in the space between the guard and discharge outlet having an article receiving pocket carried in the travel of said member from a point clear of the guard to a point in registry with the discharge outlet to thereby transfer an article received in said pocket at a point clear of the guard, in through the space between the guard and hopper into said outlet, article transfer means for acting on the article delivered into said outlet and means for supporting a member in position to receive the article delivered by said transfer means.

In witness whereof, I have hereunto set my hand this 16th day of July, 1923.

ANDREW C. HAUCK.
